UNITED STATES PATENT OFFICE.

GEORGE F. FREED, OF BEN AVON, AND JOHN R. SPENCER, OF PITTSBURGH, PENNSYLVANIA, ASSIGNORS TO PITTSBURGH GAGE & SUPPLY COMPANY, OF PITTSBURGH, PENNSYLVANIA.

SAFETY-LOCK FOR SWING-WRINGERS.

1,346,816.

Specification of Letters Patent. Patented July 20, 1920.

Application filed April 12, 1919. Serial No. 289,621.

To all whom it may concern:

Be it known that we, GEORGE F. FREED, a resident of Ben Avon, in the county of Allegheny and State of Pennsylvania, and 5 JOHN R. SPENCER, a resident of Pittsburgh, county of Allegheny, and State of Pennsylvania, have invented a new and useful Improvement in Safety-Locks for Swing-Wringers, of which the following is a specification.

This invention relates to power driven washing machines having a wringer attached and driven by the same motor.

The object of the invention is to provide 15 a lock to prevent accidental swinging out of normal operative position of the wringer attached to the washing machine. Another object is to furnish a lock for the purposes above stated, which may be readily disengaged to permit swinging adjustment of 20 the wringer, and which is simple in construction, positive in action, and economical in manufacture.

In power driven washing machines for 25 household use it is customary to mount a wringer on the washing machine frame and to drive it by a shaft from the motor used to drive the machine itself. This arrangement is described in Patent No. 1,217,540, 30 to F. W. Wappat. Such a construction, with our invention applied thereto, is illustrated in the accompanying drawings, wherein Figure 1 is a partial elevation of the washing machine and wringer attached; 35 Fig. 2 is a central vertical section, on an enlarged scale, of the wringer driving mechanism; Fig. 3 is a perspective view of a bracket for supporting the wringer; Fig. 4 is a perspective view of the locking device; 40 and Fig. 5 is an underplan and partial section showing the gear casing of the wringer attachment.

Washing machines of the type referred to 45 comprise a body or tub 1, supported by a frame 2. An agitator or drum inside the tub 1, is driven by suitable gears (not shown) incased in a housing 3 and connected to a prime mover, such as an electric motor (not shown) a shaft 4, inclosed by a circular 50 casing 5 and driven from the main driving shaft, extends vertically to a casing 6, and carries a terminal beveled gear 7, inside that casing. Beveled gear wheels 8 and 9 are idly mounted on a horizontal shaft 10, 55 which extends to and drives the rolls 11 of

the wringer. A two-faced clutch 12, splined on the shaft 10, is adapted to be thrown into engagement with one or the other of the gear wheels 8 and 9 by means of a hand lever 13 to drive the rolls of the wringer 60 in alternate directions. The gear casing 6 carries an extension 14, on the outer end of which is carried the frame 15 of the wringer. The lower end of casing 6 consists of a cylindrical extension 16, partially 65 inclosed by and seating on the upper end of the casing 5. A bracket arm 17 is fastened to the upper part of the frame of the washing machine, and this bracket clamps the casing 5 by means of a clamping 70 joint 18, having ears 19 clamped together by bolt 20, in the usual manner of such joints.

As will be obvious, when the shaft 4 and gear 7 are driven, say counter-clockwise, 75 and the clutch 12 is in engagement with the gear wheel 9, there will be a tendency to turn the entire casing 6, and the wringer supported thereon, in counter-clockwise direction, horizontally. So long as the gear 80 9 and shaft 10 turn freely, this tendency will not be strong. But if the wringer be overloaded, as by striking an unusual thickness of clothing passing between the rolls, a very strong torque will be imparted to the casing, and it will have a tendency to turn, 85 carrying the sleeve 5, which is attached to it by screw 21, in spite of the clamping joint 18. The casing will carry around the wringer mounted thereon, and the latter, 90 swinging in a horizontal plane, may strike the machine operator a severe blow. It is to avoid this not infrequent occurrence that the present invention is designed.

The particular locking device shown comprises a sleeve 22, adapted to fit loosely around the upper end of circular casing 5. The bottom of this sleeve seats on the top of bracket 17, i. e., about the upper periphery of clamping joint 18. One or more 100 teeth 23 are provided on the under edge of the sleeve 22, and interfitting coöperating teeth 24 on the upper side of the clamp 18. Both sets of teeth are inclined on one side and perpendicular on the other, so as to 105 provide an interfitting arrangement which absolutely locks the sleeve 22 against counter-clockwise rotation, but permits clockwise rotation by the beveled faces of teeth 23 riding over the beveled faces of teeth 24. 110

A plurality of slots 25 are provided in the upper edge of the sleeve, and these slots are adapted to engage depending flanges 26 on the underside of gear casing 6, as shown in Figs. 1, 4 and 5. These slots are cut deeply enough to permit the sleeve 22 to rise and disengage the two sets of ratchet teeth. When this is done and the clamp 18 loosened, the wringer and casing 6 may be swung around to any desired position, and then the locking sleeve is released, reengaging the two sets of teeth and holding the wringer in adjusted position. Consequently the position of the wringer over the tub may be readily adjusted, and the wringer locked in that position against the torque incident to driving the wringer rolls.

The simplicity of this device will be apparent. Machines of this class are usually operated by women, who have no great knowledge of mechanisms, and in such cases it is desirable to have devices not requiring adjustment, and automatic in their operation. This device provides an absolutely safe means for locking the wringer against swinging around and striking the operator, and at the same time permits ready adjustment of the position thereof.

We claim:

30 1. In combination with a frame, a vertical driven shaft mounted thereon, a wringer frame mounted on said vertical shaft to swing in a horizontal plane therearound, coöperating gears connecting the vertical 35 shaft and wringer rolls, and locking means arranged to automatically lock the wringer frame to the main frame against swinging movement in the direction of the torque imparted to the wringer frame by the driving 40 gear but allowing a swinging movement in the opposite direction.

2. In combination with a frame, a vertical driven shaft mounted thereon, a wringer frame pivotally mounted on said vertical 45 shaft to swing in a horizontal plane therearound, coöperating gears connecting the

vertical shaft and wringer rolls, a locking member fixed to the main frame, and a co-operating locking member vertically movably connected to the wringer frame, said locking members being provided with oppositely facing inclined teeth, thereby automatically locking the wringer frame against swinging movement in one direction and permitting swinging movement in the opposite direction.

3. In combination, a frame, a vertical driven shaft mounted thereon, a wringer frame pivotally mounted on said vertical shaft to swing in a horizontal plane therearound, coöperating gears connecting the vertical shaft and wringer rolls, a locking member fixed to the main frame, and a locking member vertically movably and non-rotatably attached to the wringer frame, 65 both locking members surrounding the vertical shaft and being provided with co-operating inter-engaging projections and notches.

4. In combination, a frame, a vertical 70 driven shaft mounted thereon, a wringer frame pivotally mounted on said vertical shaft to swing in a horizontal plane therearound, coöperating gears connecting the vertical shaft and wringer rolls, a locking 75 member fixed to the main frame, and a locking member vertically movably and non-rotatably attached to the wringer frame, 80 both locking members surrounding the vertical shaft and being provided with oppositely facing inclined teeth, whereby said wringer frame is automatically locked against swinging movement in one direction and permitted swinging movement in the opposite direction.

In testimony whereof we have hereunto set our hands.

GEORGE F. FREED.
JOHN R. SPENCER.
